(57) **CLAIM**

The ornamental design for a tennis bottle, as shown and described.

DESCRIPTION

FIG. 1 is a front view of a tennis bottle showing my new design;

FIG. 2 is a right side view thereof.

FIG. 3 is a left side view thereof.

FIG. 4 is a rear view thereof.

FIG. 5 is a top plan view thereof; and,

FIG. 6 is a bottom plan view thereof.

The broken lines illustrates portions of the tennis bottle that forms no part of the claimed design.
